UNITED STATES PATENT OFFICE.

WILLIAM ARNOLD OWEN, OF SALISBURY, NORTH CAROLINA.

GRATE.

Application filed May 22, 1925. Serial No. 32,177.

To all whom it may concern:

Be it known that I, WILLIAM A. OWEN, a citizen of the United States, residing at Salisbury, in the county of Rowan and State 5 of North Carolina, have invented a new and useful Grate, of which the following is a specification.

This invention relates to grates, and more particularly to grates used in open fireplaces, 10 the primary object of the invention being to provide a self-dumping grate.

An important object of the invention is to provide a device of this character which may be readily and easily removed from its 15 position within the grate frame, so that the fireplace may be converted from a coal burning fireplace to a wood burning fireplace wherein andirons may be used.

A further object of the invention is to 20 provide a pivoted grate which when released will automatically dump the contents thereof.

With the foregoing and other objects in 25 view which will appear as the description proceeds, the invention resides in the combination and arrangement of parts and in the details of construction hereinafter described and claimed, it being understood that changes in the precise embodiment of 30 the invention herein disclosed, may be made within the scope of what is claimed, without departing from the spirit of the invention.

Referring to the drawing:

Figure 1 is a front elevational view of a 35 grate constructed in accordance with the invention.

Figure 2 is a sectional view taken on line 2-2 of Figure 1.

Figure 3 is a sectional view taken on line 40 3-3 of Figure 1.

Referring to the drawing in detail, the frame of the grate includes side bars 5 to which the supporting pins 6 are secured, the supporting pins extending inwardly 45 from the side bars, as clearly shown by Figure 1 of the drawing.

The grate is of a novel construction and includes a plurality of angle bars 7 that are arranged in spaced relation with each 50 other and held in such spaced relation by means of the lower bar 8 and upper bar 9.

These angle bars are constructed to provide horizontal sections 10 and vertical sections 11, the forward surfaces of the end

angle bars being cut away to provide depending fingers 12 that lie in spaced relation with the vertical sections 11 of the angle bars of which they form a part so that the fingers 12 may be positioned over the pins 6 to pivotally support the grate. 55 60

Adjacent to the bar 9 are pivoted latch members 13 that are adapted to engage the bar 9 adjacent to its ends to prevent the grate from tilting rearwardly and discharging the contents thereof. 65

Above the latch members 13 are pins 14 that are adapted to restrict movement of the latch members to insure the latch members being held in proper positions to engage over the bar 9, as illustrated by Figure 70 2 of the drawing. From the foregoing it will be obvious that when coals are positioned on the horizontal sections 10 of the handle bars, a downward pressure will be exerted on the grate to the end that it is 75 only necessary to move the latch members to disengage the bar 9 when it is desired to dump the grate, it being obvious that the weight of the coals on the horizontal sections 10 will overbalance the grate causing 80 it to dump its contents.

Should it be desired to remove the grate to clean the fireplace or to substitute andirons for the coal grate, it is only necessary to operate the latch members to cause them 85 to release the grate body portion, whereupon the grate will swing to dotted lines as shown by Figure 2 of the drawing, to the end that it may be readily lifted from the pins 6. 90

I claim:—

A dumping grate including a frame, inwardly extended pins secured to the frame, a grate body portion including an inwardly extended supporting surface, fingers 95 forming a part of the grate body, said fingers being arranged in spaced relation with the grate body to permit the fingers to be positioned over the pins, and pivoted latch members carried by the frame and adapted to engage over the upper edge of the grate body to normally hold the grate body in its active position. 100

In testimony that I claim the foregoing as my own, I have hereto affixed my signature. 105

WILLIAM ARNOLD OWEN.
